UNITED STATES PATENT OFFICE.

ROBERT CHARLES COLE, OF WEST HARTFORD, CONNECTICUT, ASSIGNOR TO THE JOHNS-
PRATT COMPANY, OF HARTFORD, CONNECTICUT, A CORPORATION OF CONNECTICUT.

INDICATOR FOR INCLOSED FUSES.

1,040,150.

Specification of Letters Patent.

Patented Oct. 1, 1912.

Application filed June 10, 1911. Serial No. 632,483.

To all whom it may concern:

Be it known that I, ROBERT CHARLES COLE, a citizen of the United States, residing at West Hartford, in the county of 5 Hartford and State of Connecticut, have invented a new and useful Improvement in Indicators for Inclosed Fuses, of which the following is a specification.

This invention relates to a method of 10 constructing an indicating inclosed electric fuse.

It is common practice to so connect a fine indicator wire between the terminals of an inclosed electric fuse, that, when the main 15 fuse is blown by an overload or short circuit, the heat generated by the current which passes through the indicator wire will effect the disruption of the latter or will cause a discoloration of a spot, or a portion of the 20 fuse label, or will ignite a small quantity of inflammable material which will discolor or fracture the label or spot, for the purpose of visually indicating the fact that the main fuse has been disrupted. In order to effectually accomplish this, it has been customary 25 to drill very small holes through the tubular fiber casing usually employed, and to thread the fine indicator wire through these small holes, so that the active portion of the wire 30 will lie on or near the outer surface of the casing. The holes through which the wire is thus threaded must of necessity be very small so that dangerous flame and filling 35 material will not be blown through them when the fusible strip is disrupted. The expense of drilling these small holes in the fiber tube which is ordinarily used as the 40 inclosing case, and threading the very fine indicator wire through such holes, has been large in proportion to the cost of constructing the rest of the fuse.

The object of this invention is to so construct the casing and simplify the method of applying the indicator wire as to materially 45 reduce the cost of manufacture and at the same time increase the reliability of such fuses.

Figure 1 of the accompanying drawings 50 is a side view of an inclosed electric fuse which embodies this invention. Fig. 2 shows a central longitudinal section of the same.

The casing of the fuse illustrated is made as usual of a fiber tube 1. On and closing 55 the ends of this tubular casing are the me-

tallic ferrules 2, to which it is customary to electrically connect the ends of the fusible member 3. Granular filling material may or may not as preferred be placed in the casing about the fusible member. 60

In carrying out this invention, three holes are punched in the side of the fiber tube, one near each end and one between, desirably near the middle. The fine indicator wire 4 is run along the inside of the casing. An eyelet 5, desirably coated with insulating enamel, is forced from the interior into the intermediate hole. This eyelet pushes a section of the indicator wire from the interior of the casing into the hole and tightly 70 closes the hole so that no flame or filling material can be blown out when the main fuse is melted, even under severe short circuit conditions. With the eyelet arranged in this way, the greater the pressure of gas 75 when the main fuse is blown, the tighter will the hole be closed. In the intermediate hole, adjacent to the indicator wire, it is desirable to place a disk or pellet 6 of inflammable material, which may or may not be 80 attached to the label 7 that is applied to the tubular casing over this hole. The ends of the indicator wire are passed through the holes punched near the ends of the casing and are secured therein by eyelets 8 which 85 are forced into the holes from the outside. These eyelets, beside closing the holes and securing the ends of the indicator wire, insure 90 electrical connection between the indicator wire and the terminal ferrules which close the ends of the casing.

A fuse constructed in this manner is cheap to manufacture, for the three holes may be of considerable size and can be rapidly punched by common machinery. The eyelets may be inserted by a suitable machine and when inserted they close the openings and at the same time retain the indicator wire in a suitable manner. When the main fuse blows, and the current is diverted through the indicator wire, that wire becomes heated and ignites the inflammable material which burns or discolors the label. 95

The invention claimed is:

1. An inclosed fuse having a tubular casing with an opening through one side, an imperforate eyelet with a closed outer end forced from the interior into and closing said opening, and an indicator wire extending along the interior of the casing and 100
- 105
- 110

forced by said eyelet into the opening so that a section of said wire passes across the exterior of the closed end of the eyelet.

2. An inclosed fuse having a tubular casing with an opening through one side, an imperforate eyelet with a closed outer end forced from the interior into and closing said opening, an indicator wire extending along the interior of the casing and forced 10 by said eyelet into the opening so a section of said wire passes across the exterior of the closed end of the eyelet, and material adapted to undergo a change when the indicator wire becomes heated, located in said opening 15 in contact with the exterior section of the wire.

3. An inclosed fuse having a tubular casing with an opening through one side, an eyelet with a flanged inner edge, and a closed 20 outer end forming a closure for said opening through the side of the tube, and an indicator wire extending along the interior of the casing and over the exterior surface of the eyelet.

25. 4. An inclosed fuse having a tubular casing with three openings in one side, an indi-

cator wire extending along the interior of the casing and having its ends extending through the end openings, eyelets inserted into the end openings from the outside and 30 binding the ends of the indicator wire, and an eyelet inserted into the intermediate opening from the interior and forcing the indicator wire into said intermediate opening.

5. An inclosed fuse having a tubular cas- 35 ing with three openings through its side, an indicator wire extending along the interior and having its ends extending through the end openings, eyelets inserted from the interior into the end openings and 40 binding the ends of the indicator wire, and eyelet inserted from the interior into the intermediate opening and forcing said indicator wire into the intermediate opening, and metallic end caps closing the ends of 45 said casing and engaging the eyelets in the end openings.

ROBERT CHARLES COLE.
